UNITED STATES PATENT OFFICE.

COMMIE L. ENNIS, OF BOYKINS, VIRGINIA.

SAFETY APPLIANCE FOR LANTERNS.

Application filed June 2, 1924. Serial No. 717,437.

My invention relates to certain new and useful improvements in safety appliances for use in connection with crossing lamps, particularly employed in railroading, and 5 the invention has for its object to provide means by which the red or danger signal railroad lamp can be used without the necessity of special construction and to provide means that will permit the red light to be 10 seen by pedestrians or vehicular traffic which may be approaching the railroad crossing, while shielding the light from the engineer or trainmen's vision when the train is approaching the crossing, thus preventing 15 the train crew from becoming confused as to signals.

My invention consists in providing a tubular section and stamping from it pairs of wings which are bent radially and serve as 20 blinds in two directions, allowing the light to be seen from two directions at angles of ninety degrees from the blind, or in other words, permitting the red light to be seen by those approaching the railroad crossing 25 by the road while shielding the light against the vision of the engineer or train crew approaching the crossing on the track.

The invention also provides a means for holding the attachment on the base of an 30 ordinary railroad lamp, thereby not interfering with the manipulations of the lamp itself when it is desired to clean it or to light or extinguish it.

In the drawings:—

35 Figure 1 is a perspective view illustrating my invention applied to the lamp.

Figure 2 is a perspective view of my attachment per se.

40 Figure 3 is an inverted plan view of the same showing the resting lugs by which the attachment is held in place on the railroad lamp.

45 In the drawings, 1 represents the cylindrical section which may be made of an ordinary piece of galvanized iron stove pipe and from which is stamped, on two sides, the ears or blinds 2—2, the latter being flattened and bent to lie in planes intersecting

the axis of the cylindrical section. The stamping of the blinds 2—2 provides openings 3 in alignment with each other and these openings, when the attachment is on the lamp, are located in a direction at right angles to the track so that the lamp may be viewed by those approaching the railroad 55 crossing while the light is shielded from the view of the engineer or firemen on the approaching train.

At the bottom the cylindrical section has lugs 4 stamped therefrom and bent inwardly to rest on the flange of the lamp 6, thus leaving the lamp top 7 free to be raised or lowered as may be desired in order to clean the lamp or to light or extinguish it.

The cylindrical section 1 if made from 65 galvanized iron may be made from flat sheet metal and bent into the form of a cylinder with the edges overlapping, as at 8, and riveted together as at 9.

It will be seen from the foregoing taken 70 in connection with the accompanying drawing, that my invention is of a simple and effective construction, can be easily and cheaply manufactured, readily placed in position on the ordinary railroad lamp and will not 75 interfere with the normal operation of the lamp itself.

From the foregoing description, taken in connection with the accompanying drawing, it is thought that the complete construction, 80 operation and advantages of my invention will be clear to those skilled in the art.

What I claim is:—

In combination with a railroad crossing lamp, of a tubular casing open top and bottom and adapted to be set over the lamp, said 85 casing having lugs at the bottom serving as feet to rest on the base flange of the lamp, blinds stamped from the casing on two sides and bent to lie in planes intersecting the 90 axis of the casing, thereby presenting diametrically opposite light openings and diametrically opposite "blinds", the latter being located ninety degrees from the former, substantially as shown and described.

COMMIE L. ENNIS.
